UNITED STATES PATENT OFFICE

JOHN M. SHIELDS, OF CHICAGO, ILLINOIS, ASSIGNOR TO F. H. NOBLE & CO., OF CHICAGO, ILLINOIS, A CORPORATION OF ILLINOIS

METHOD OF FORMING JEWELRY CASES AND SIMILAR CONTAINERS

Application filed January 26, 1928. Serial No. 249,537.

This invention relates to improvements in jewelry cases and its purpose is to provide a novel and useful method for forming an improved case adapted for use as a container for watches, jewelry, pens and pencils, and various other articles. The principal object of the invention is to provide for conveniently and readily forming at small cost the improved jewelry case herein described by stamping and punching from sheet metal a box body member or frame member in which the parts necessary to the formation of the complete box or container may be readily assembled without the use of auxiliary fastening means. In my separate application for patent filed as a division of this application on June 20, 1929, Serial No. 372,260, for improvement in sheet metal boxes, I have presented claims for the improved box or case which will herein be described.

The nature of the invention will be understood from the following specification taken with the accompanying drawings in which the form of the improved jewelry case above referred to and my improved method of forming the same are illustrated. In the drawings,

Fig. 1 shows a perspective view of the sheet metal blank from which the frame structure of the box or lower part of the jewelry case is formed;

Fig. 2 is a perspective view of the sheet metal blank after the first punching operation has been performed thereon in the process of making the frame structure of the container and after the covering material forming the exterior finish of the box body has been applied, a portion of this covering material being broken away to show a depression formed in the metal blank to accommodate the roll of the hinge of the box;

Fig. 3 is a perspective view similar to that of Fig. 2 showing the arrangement of the parts after the next succeeding punching operation of the covered blank;

Fig. 4 is a perspective view similar to that of Fig. 3 showing the relative arrangement of the parts after a still further punching and bending operation has been performed on the covered sheet metal structure;

Fig. 5 is a perspective view showing the structure illustrated in Fig. 4 with the cover and hinges of the case applied thereto and with an outer lining applied on the inside of the box;

Fig. 6 is a cross-sectional view taken at right angles to the axes of the hinges illustrated in Fig. 5;

Fig. 7 is a perspective view similar to that of Fig. 5 showing the complete jewelry case with all of the linings and other interior members applied;

Fig. 8 is a transverse sectional view through the box and cover with the linings and other interior parts removed, the cover being in closed position; and

Fig. 9 is an enlarged cross-sectional view taken transversely of the jewelry case with all parts thereof in place and with the cover in closed position.

In the manufacture of the jewelry case by the method of the present invention the first step is the formation of the frame structure of the box body or lower portion of the case to which a hinged cover is subsequently to be applied. Instead of forming this box body from cardboard or the like according to the practice heretofore usually prevailing, the present invention contemplates the formation of such body member from a flat sheet of metal 10 having the rectangular form illustrated in Fig. 1, although other forms of the sheet metal blank may be employed where the shape of the final jewelry case is to be other than rectangular. After cutting the

blank 10 to the proper size, the next operation is to place the blank in a suitable die punching machine or the like and, by a single punching operation, project the lateral edges of the blank downwardly and outwardly, and also form the depressions *a-a* for the hinge roll. At this stage of manufacture the blank is covered with the covering 21 of leather, imitation leather, fabric or the like, which conforms to the contour of the blank, and is secured thereto by glue, or other suitable adhesive, this covering extending around the edges of the connected side flanges 12 and end flanges 13 which in the present instance flare outwardly and downwardly in straight lines

from the central portion 11 and in the completed box forms the inclined outer walls of the box body. Obviously the flanges 12 and 13 may be formed on curved lines, if desired, to give any desired pleasing contour to the outer walls. This box body thus formed as shown in Fig. 2, is then operated upon by other cutting and punching dies to remove a portion of the covered metal from the top plate 11 and leave an irregular opening 14 therein bounded by inwardly directed flanges on its four sides. The flanges on the longer sides of the opening 14 have inwardly projecting extensions 15 while the flanges at the ends of the opening 14 have inwardly directed extensions 16. In addition, the flange along one of the longer sides of the opening 14 has a plurality of openings 17 punched therein to form small upwardly directed tongues 18.

The next operation in the formation of the body member of the case is to bend the flanges around the opening 14 downwardly while at the same time projecting the extensions 15 and 16 inwardly in a horizontal plane, as shown in Fig. 4, where the flanges have been bent downwardly into vertical planes to form opposite inner side walls 19 and transverse inner end walls 20. The flanges 15 extend inwardly in a horizontal plane from the walls 19 while the flanges 16 extend horizontally inward in the same plane from the end walls 20. At the same time, the small tongues 18 have been caused to project inwardly above the position occupied by one of the flanges 15. This represents the final formation of the lower frame structure of the body of the case and the flanges 15 and 16 are adapted to support certain parts of the completed box.

As shown in Fig. 5 of the drawings the edges of the covering material 21 within the frame structure are protected by a surrounding lining member 22 which is in the form of a band of relatively stiff fabric or other material having its lower edges resting on the flanges 15 and 16 and having its upper edges terminating substantially flush with the upper edges 23 of the surrounding frame to which the covering 21 has been applied. The ends 22^a of the lining member 22 are preferably secured in place by glue or the like.

As further shown in Fig. 5, the partially completed case also comprises a cover 25 having a top wall member 25^a bounded by an integral surrounding flange 25^b which is formed by punching a sheet metal plate to project the surrounding flanges transversely thereto. At the same time the top wall 25^a may be punched to form a rectangular elevated portion 25^c. This cover has a layer of leather, imitation leather or other covering material 26 applied thereto by glue or the like with the edges thereof carried upwardly inside of the flanges 25^b. The edges 65 of the flanges 25^b are adapted to coincide

with the edges 23 of the lower box frame when the cover is closed. The lower frame structure and the cover 25 are secured together by hinges 27 and each hinge member is provided with apertures adapted to be engaged by the tongues 18 formed on the lower frame and by the other tongues 28 formed on the cover. The tongues on the cover are formed by punching in the same way that the tongues 18 were formed and after the hinges 27 are fitted in place with these tongues engaging the apertures therein, the tongues are bent transversely to hold the hinges firmly in place, the depressions a—a formed in the box body member receiving the hinge rolls to permit a close seating of the cover upon the box. Each of the pivotally connected hinge members is provided with a notch as shown at 29 to be engaged by a curved leaf spring 30 having substantially the form of the letter C with the ends thereof hooked about the edges of the hinge members at the bottoms of the notches 29. These spring members are such that they will hold the cover 25 in either an open or closed position after the cover is swung beyond an intermediate neutral point. In Fig. 6 of the drawings the springs 30 are shown as serving to hold the cover 25 in its open position while in Fig. 8 they are illustrated in position to maintain the cover closed.

After the parts have been formed and assembled in the manner illustrated in Fig. 5, the lining members and jewelry tray or support are put in place. The first step is to place a strip of silk 32 or the like over the hinges and the hinge joint longitudinally of the box and of sufficient width to overlap the adjacent bottom flange 15 and also the top wall 25^a of the cover. After applying 105 glue or paste to the inside of the cover, a cover lining member 33 is then put in place overlapping the outer side of one edge of the hinge covering 32. This cover lining 33 may preferably be a sheet of cardboard or a rectangular cardboard frame covered with silk or other material similar to that forming the hinge covering 32 and upon engaging the paste or glue applied to the inside of the cover it will be held in place and will 110 at the same time hold the hinge covering 32 in place by friction. If the body structure of the cover lining 33 has sufficient stiffness and resiliency it may be caused to retain itself in position without employing any glue 115 or other fastening means.

A sheet of cardboard 34 constituting an inner bottom wall is then placed in the bottom of the lower frame structure with its edges resting on the flanges 15 and 16 and of such a size that it fits closely within the outer lining strip 22. One edge of the cardboard sheet 34 will rest on the edge of the hinge covering 32 and hold the lower part thereof 120 in place. The parts are then in readiness 125 130

for the insertion of the jewelry tray or support 35 which is preferably made up of a sheet metal frame 36 stamped from a sheet metal blank to form downwardly extending outer flanges 36^a and one or more intermediate depressions 37, the single depression 37 shown in Figs. 7 and 9 being of suitable shape to receive a wrist watch and its connected wrist band. The sheet metal frame 36 of the jewelry tray has an outer covering 38 of plush or the like, the lower edges of which are turned upwardly on the insides of the flanges 36^a and secured in place by a sheet 39 of cardboard or sheet metal. The plush lining 38 conforms to the contour of the depression 37 which is enlarged at one end as shown in Fig. 7 to receive the watch. This jewelry tray preferably has a tab 40 attached to the side thereof so that it may be pulled upwardly and replaced by another tray having a depression of different conformation to receive another article of jewelry of different shape. This tray is held in place by gravity and by frictional contact with the surrounding lining member 22. The opening between the surrounding walls formed by the covered flanges 12 and 13 of the box beneath the tray is closed by an outer bottom wall 41 made up of a sheet 41^a of cardboard or sheet metal having a covering 41^b of leather or the like applied to the lower surface thereof. This outer bottom wall 41 lies immediately below the flanges 15 and 16 of the box body, adjacent the inner wall or cardboard sheet 34 resting on top of such flanges, and is glued to such sheet to secure the parts together and complete the box body, the flexibility of the wall members being sufficient to permit a firm glued connection to be made.

Although one form of the invention has been shown and described in connection with one method of forming the improved jewelry case, it will be understood that the invention may be embodied in various forms and practiced in various ways within the scope of the appended claims.

I claim:

1. The method of forming a box body member for a jewelry case or the like which comprises the operations of forming a sheet metal blank, bending the edges of said blank downwardly to form outer walls, punching the intermediate part of said blank to form an opening surrounded by inwardly directed flanges, and bending said flanges to form inner walls having supporting flanges extending inwardly therefrom.

2. The method of forming a box body member for a jewelry case or the like which comprises the operations of forming a sheet metal blank, bending the edges of said blank downwardly to form outer walls, then securing a covering of flexible material to said bent blank, afterwards punching the intermediate

part of said blank to form an opening surrounded by inwardly directed flanges, and then bending said flanges downwardly to form inner walls having supporting flanges extending inwardly therefrom.

3. The method of forming a box body member for a jewelry case or the like which comprises the operations of forming a sheet metal blank, bending the edges of said blank downwardly to form outer walls, punching the intermediate part of said blank to form an opening surrounded by inwardly directed flanges, punching one of said flanges to form upwardly extending tongues, and bending said flanges downwardly and inwardly to form inner walls having supporting flanges extending inwardly from their lower edges.

4. The method of forming a box body member for a jewelry case or the like which comprises the operations of forming a sheet metal blank, bending the edges of said blank downwardly to form outer walls, then securing a covering of flexible material to said bent blank punching the intermediate part of said covered blank to form an opening surrounded by inwardly directed flanges, punching one of said flanges to form upwardly extending tongues, and bending said flanges downwardly and inwardly to form inner walls having supporting flanges extending inwardly from their lower edges and on one wall having said tongues extending inwardly.

5. The method of forming a box body member for a jewelry case or the like which comprises the operations of forming a sheet metal blank, bending the edges of said blank downwardly to form outer walls, then securing a covering of flexible material to said bent blank, afterwards punching the intermediate part of said blank to simultaneously form an opening surrounded by inwardly directed flanges and upwardly extending tongues on one of said flanges, and then bending said flanges downwardly to form inner walls having inwardly extending supporting flanges and having on one wall said tongues extending inwardly.

6. The method of forming a jewelry case or the like which comprises the operations of forming a sheet metal blank, cutting out an intermediate part of said blank to form an opening having inwardly directed flanges on the sides thereof, bending the metal around said opening downwardly to form the inner walls of a box, bending said flanges inwardly from the lower edges of said inner walls, and placing a tray on said flanges.

7. The method of forming a jewelry case which comprises the operations of forming a sheet metal blank, cutting a rectangular opening in an intermediate part of said blank with oppositely disposed flanges extending inwardly on opposite sides of said opening,

punching the metal of said blank outwardly from one of said flanges to form upwardly projecting tongues, bending the metal around said opening downwardly to form vertical inner walls one of which carries said tongues projecting inwardly, placing perforated hinge members over said tongues and bending said tongues, and attaching a cover to said hinge members.

- 10 8. The method of forming a jewelry case which comprises the operations of forming a sheet metal blank, bending the edges of said blank downwardly to form outwardly flared outer walls, forming an opening in the intermediate part of said blank surrounded by inwardly directed flanges, punching the metal of said blank constituting one of said flanges to form upwardly directed tongues, bending the metal of said blank downwardly around said opening to form inner walls of which one wall carries said tongues directed inwardly and bending said flanges transversely to form horizontal flanges at the lower edges of said inner walls, attaching hinges to said tongues, and attaching a cover to said hinges.
- 15 20 25

In testimony whereof, I have subscribed my name.

JOHN M. SHIELDS.
